SPIRIT LEVEL

Theodore F. Vaida, High Bridge, N. J.

Application September 5, 1946, Serial No. 694,925

1 Claim. (Cl. 33—211)

1

This invention relates to spirit levels or the like embodying the advantages inherent both to wooden and metallic-bodied levels of this character.

Principal objects of the invention are to provide durable levels constructed both of wood and of metal which are highly resistant to wear, lighter in weight than an all metal level, non-warping and highly resistant to breakage.

A further object of the invention is to provide levels that are simple in construction and which may be manufactured simply and at comparatively low cost.

To the accomplishment of the foregoing and such other objects as may hereinafter appear, this invention consists in the novel construction and arrangement of parts hereinafter to be described and then sought to be defined in the appended claim, reference being had to the accompanying drawing forming a part hereof, which shows, merely for the purposes of illustrative disclosure, a preferred embodiment of the invention, it being expressly understood, however, that changes may be made in practice within the scope of the claim without digressing from the inventive idea.

In the drawing, wherein similar reference characters denote corresponding parts:

Fig. 1 is an elevational view of a level embodying the invention;

Fig. 2 is an enlarged partial vertical elevation with portions broken away to show structural details;

Fig. 3 is a vertical section taken along line 3—3 of Fig. 2;

Fig. 4 is a longitudinal vertical section taken along line 4—4 of Fig. 3;

Fig. 5 is a vertical section taken along line 5—5 of Fig. 2; and

Fig. 6 is a fragmentary perspective view showing further structural details.

Referring to the drawing, 10 denotes the level. This level comprises a metal core or ply 11 of cast aluminum or other metal and consisting of segments 12 and 13 joined end to end, for example, by the dovetail joints 14. These segments 12, 13 have substantially I beam sections and are provided with opposite outer flanges 12a, 13a and with aligned longitudinally oppositely-extending reinforcing ribs 12b, 13b. The segments 12 are each provided with a large hole 15 defined by the oppositely extending lateral annular flanges 16, 17. Abutments 18 integral with the segments 12 extend inwardly of the opening 15 at diametrically opposite points and serve for mounting of one or more leveling fluid-containing vials 19, 20 as will be presently described.

2

Wooden facing members or plies 21, 22 are secured permanently to the opposite faces of the joined segments 12, 13. These wooden facing members 21, 22 originally are of somewhat greater dimensions than the segments 12, 13. The internal faces of these members 21, 22 have longitudinal grooves 23, 24, 25 and 26 admeasured to receive respectively the ribs 12b, 13b and the outer flanges 12a, 13a so that in effect these internal faces are complementary in shape with the respective outer side faces of the segments 12, 13. The wooden facing members 21, 22 also have holes 27, 28 admeasured in diameter to fit snugly around the lateral flanges, 16 and 17.

15 In assembling the parts so far described, sufficient of the segments 12, 13 are joined end to end by interengagement of their dovetail joint parts

14 to constitute the desired level length. The opposite ribbed side surfaces of these segments are

20 then coated with an adhesive resin, hereinafter to be described. The internal, grooved faces of the wooden facing members 21, 22 of desired length then have an adhesive undercoating resin presently to be described applied thereto, and an

25 overcoat of the first-mentioned resin. The so coated facing wooden members or plies 21, 22 are then fitted and applied to the opposite ribbed surfaces of the resin coated segments 12, 13 and the interfitted parts are forced intimately together

30 under heat and pressure to bond the parts permanently together on their resin-coated surfaces. The resin bonds are permanent, very strong, and the resultant ply structure consisting of an inner metallic ply or core sandwiched between outer wood plies or layers 21, 22 is very strong and not liable to deformation. Likewise the resin bonds hold firmly under varying atmospheric conditions.

When the wooden plies 21, 22 and inner metallic

35 ply or core 11 have been bonded together as described, the wooden layers or plies 21, 22 are

40 trimmed or ground flush with the outer surfaces of the metallic ply and the bottom surfaces of the combined plies ground smooth and flush to form a suitable base for the level 10.

45 When this has been completed vial holders 30 in the form of insertable rings carrying one or

more leveling fluid-containing vials 19, 20 are

50 inserted into the openings 15 and secured conventionally as by screws 31 to the abutments

55 18. The latter are arranged with respect to the various openings 15 so that the vials 19 in some

openings 15 are substantially parallel with the longitudinal axis of the level and in others are at 90 degrees therewith or at any other desirable angles.

When the rings 31 have been secured as described, annular washers or rings 32

of aluminum or other material, are applied to overlie the abutments 18 and conceal the joints between the latter and rings 30. Transparent cover plates 33 of glass or other suitable material are then applied over the rings 32 and these cover plates 33 are secured in place by resilient, split spring or snap retaining rings 34 preferably of steel which are deformable sufficiently to permit their insertion within the annular flanges 16, 17 overlying the plates 33 at their rims. These spring retaining rings 34 engage frictionally with the inner walls of flanges 16 and 17 and hold the plates 33 securely in place on opposite sides of the vials 19, 20. They may be removed readily if necessary for the replacement of parts. It will be seen that the vials 19, 20, their rings 30, and the transparent cover plates 33 are exclusively and securely held in place within the metallic elements 12. They are nowhere in contact with wooden parts.

The combined metallic internal ply or core 11 and external wooden plies or layers 21, 22 produce a structure which has high resistance to wear on the working edges because the center of the working edge is a metallic edge formed by the edges of the flanges of the metallic cores 12, 13. The structure is of reduced weight in comparison with an all metal level because its core only is of metal. The wood on the side faces is so firmly bonded to the metal core that the possibility of warping is eliminated. The structure is highly resistant to breakage or deformation. The metal core 11 would not break if the instrument fell but might tend to bend. However, the wood facing is very resistant to elongation and since it is so firmly bonded to the metal core on opposite faces any bending tendency of the core would require elongation of the wood on one face and compression on the other face. The wood would resist such action and, therefore, prevent bending of the core and consequent deformation of the level. A tough durable level, therefore, is produced by the structure described.

Suitable bonding material for joining the wood and metal cores is of course necessary. In practice, bonding materials of resinous nature have been found to be most suitable. The resin used most successfully for coating of the metal surface of core 12, 13 is a product formed of a "DuPont" adhesive known as "J-58-0027 (4653)" and a "DuPont" catalyst known as JC-100-X-6858." The resin applied as a first or under-coat to the inner surfaces of the wooden plies 21, 22 is a "Plywood" product known as "Pliobond Plastic Adhesive." Other suitable resinous or other types of bonding agents that produce strong bonds when subjected to heat and pressure and which are resistant to atmospheric changes can, of course, be used.

Likewise the specific manner of mounting the

spirit containing vials 19, 20 may be modified or changed. In addition, if desired, the metallic core segments 12, 13 may be formed initially as integral units of desired length. These segments preferably are of cast aluminum but other suitable metals may be used for their production.

Various other modifications in structure or material may be made and are contemplated. There is no intention of limitation to the exact details shown and described.

What is claimed is:

A level of the character described comprising a metallic core having substantially I beam section and having longitudinally extending ribs on its opposite side faces, said core having an opening extending transversely between said opposite side faces, annular, lateral, oppositely-extending flanges integral with said core positioned around said opening, abutments integral with said core and extending inwardly of said opening, wooden facing plies having inner surfaces complementary in shape to the side faces of said metallic core, said plies being adhesively bonded permanently one to each opposite side face of said metallic core, said plies being coextensive with said side faces with their peripheral edges lying flush with corresponding peripheral edges of said metallic core, said plies each having an opening aligned with the opening in said metallic core into each of which one of the oppositely-extending flanges of said core fits, spirit vial supporting means positioned entirely in the opening in said metallic core, and securing means for attaching said spirit vial supporting means to said abutments of said core.
